UNITED STATES PATENT OFFICE.

IRA W. NONNEMAN, OF WARREN, OHIO, ASSIGNOR TO THE BORDEN COMPANY, OF WARREN, OHIO, A CORPORATION OF OHIO.

Diestock.

1,418,323.

Specification of Letters Patent. Patented June 6, 1922.

Application filed January 14, 1920. Serial No. 351,463.

To all whom it may concern:

Be it known that I, IRA W. NONNEMAN, a citizen of the United States, residing at Warren, in the county of Trumbull and 5 State of Ohio, have invented a certain new and useful Improvement in a Diestock, of which the following is a full, clear, and exact description, reference being had to the accompanying drawings.

10 This invention relates to a die stock of the ratchet type wherein the chasers are carried by a member or frame removably extending into a handle-frame or driving member which carries a pawl coacting with 15 teeth on the chaser-carrying member. The general object of the invention is to simplify and cheapen the construction of such die stocks. More specifically an object is to so construct the pawl and chaser carrying 20 frame that the latter will be normally held by the pawl itself against removal from the handle frame, or may be removed whenever desired by simply releasing the pawl. Another object is to provide for effectively 25 holding the chaser by means which will enable its ready removal. The invention is hereinafter more fully described in connection with the drawings showing a preferred embodiment of it, and the essential characteristics are summarized in the claims.

In the drawings Fig. 1 is an end view of my die stock, looking at the end distant from the chasers; Fig. 2 is a side elevation of the die stock; Fig. 3 is an end view looking at 35 the chaser end of the die stock; Fig. 4 is a cross section through the pawl-carrying frame, as indicated by the line 4—4 in Fig. 2, this view showing the pawl in the position it has when the pawl frame is moving backwardly across the tooth to be engaged and fed; Fig. 5 is a longitudinal cross section as indicated by the line 5—5 in Fig. 1; Fig. 6 is a fragmentary cross section in the same 40 plane as Fig. 4, showing die stock in feeding engagement with one of the teeth of the chaser frame; Figs. 7 and 8 are details showing the means for locking the chasers in place, being cross sections substantially on the lines 7—7 and 8—8 in Fig. 3.

50 In the drawings, 10 indicates the chaser carrying member or frame which is composed of an annular head portion carrying the chasers and a sleeve extension 11 adapted to occupy the driving frame 40. This ex-

55 tension 11 is preferably of reduced internal and external diameter from the chaser carrying portion, the interior of the sleeve 11 constituting the pipe guide.

The chasers, designated 20, are carried in radial notches in the head 10 and locked in 60 place by longitudinal pins 35 which have a drive fit in the frame and freely occupy holes 22 in the edges of the chasers, and by an annular clamping plate 30, which has on 65 its inner face an annular rib 31 occupying notches 21 in the chasers and an annular groove in the face of the head 10. This rib effectively positions the ring, which is held to the frame in a suitable manner as by screws 32. The chasers are thus engaged at 70 their inner and outer edges and effectively locked in place but may be readily released for changing by simply removing the ring.

The outer face of the sleeve 11 of the chaser frame is provided with equi-distant 75 longitudinally extending teeth 14, which have their walls lying substantially radially. Surrounding the teeth 14 is the driving frame 40, the inner edge of which preferably abuts the shoulder 15 where the reduced 80 sleeve 11 leaves the head 10 of the chaser frame. The other edge of the driving sleeve may be flush with the sleeve 11. This driving sleeve carries a radial socket 41 from which extends the operating handle 42, 85 partly shown in the drawings, by which the frame may be oscillated.

Adjacent to the socket 41 is another radial socket 43, and in this is mounted a pawl 50 adapted to coact with the teeth 14. The 90 pawl has a shank 51 extending outwardly through an opening in the end of the socket 43 which is otherwise closed at the outer end. Surrounding this shank is a helical spring 53 compressed between the end of the socket 95 and pawl. A suitable head or knob 55 is secured to the end of the shank 51.

The inner end of the pawl 50 is peculiarly formed, its forward inner corner being rabbed to provide a tooth 56 having a radial 100 face and adapted to engage the radial face of any tooth 14, while at the rear of this radial face 56 is an inclined surface 57. On the backward movement of the pawl carrier this surface 57 engages the edge of the tooth 105 14 just behind the one which has been engaged and this cams the pawl outwardly so that it rides freely over the tooth as shown

in Fig. 4 and then drops into place behind the tooth, ready to feed it when the carrier is swung forwardly. It will thus be seen that the teeth and pawl device constitutes a 5 ratchet connection enabling oscillations of the handle to feed the chasers intermittently forward.

To prevent separation between the chaser frame and the pawl frame, I form a transverse groove 17 entirely around the chaser frame intersecting the teeth in their mid region, and I form on the under face of the inclined end 57 of the pawl a wing 58 which constantly occupies this groove. The groove 15 in reality consists of a series of aligned notches through the successive teeth, but, in effect it is an annular groove though successively interrupted. The wing 58 extends in the circumferential direction farther than 20 the distance between teeth and extends inwardly beyond the point 56 so that, in normal operation, it is always in engagement with the sleeve 11, whether the pawl be in its feeding position, as shown in Fig. 6, or is 25 passing backwardly across the top of a tooth, as shown in Fig. 4.

To release the chaser carrying frame, it is only necessary to pull the pawl outwardly beyond any of its normal positions, thus causing 30 the wing 58 to entirely clear the groove 17, enabling the chaser sleeve to be freely drawn out. The wing serves the purpose of normally holding the two frames together and also prevents the pawl being rotated out 35 of position. When desired to reverse the direction of rotation it is only necessary to draw the pawl well out and turn it half way around and allow it to return.

It will be seen that my die stock is very 40 simple in construction. The two frame members may readily be each an integral casting. The chasers are firmly held to the chaser frame by the ring 30 held by its screws. The pawl shank may be readily rigid with 45 the pawl head, the shank after being put in place through the spring and the end of the socket being riveted to the pawl head 55. No other means are necessary for holding the pawl and spring in place. The simple 50 provision of the annular groove and the wing on the pawl effectively locks the two frames together but enables their immediate release whenever desired.

I claim:

55 1. A combination of a chaser carrying frame, a driving frame, teeth on one of said frames, a pawl carried by the other frame adapted to engage the teeth, and means whereby said pawl normally prevents separation 60 of the two frames but allows such separation when desired.

2. In a die stock, the combination with two frames mutually rotatable, a chaser carried by one of the frames, and a pawl carried by 65 the other and adapted to engage teeth on

the chaser frame, said pawl having a projection normally occupying a groove in the chaser frame.

3. In a die stock, the combination of a chaser-carrying frame having a sleeve portion with external teeth, a driving frame surrounding said teeth, there being an annular interrupted groove across the teeth and a pawl carried by the driving frame having a projection normally occupying said 70 75 groove.

4. In a die stock, the combination of a chaser carrying frame, having a sleeve with external longitudinal teeth, a driving frame rotatably surrounding said teeth and having 80 a socket, a pawl mounted in said socket, and a spring pressing said pawl inwardly, said pawl having a tooth adapted to engage the teeth on the chaser frame, said pawl having also a wing at its inner end normally occupying 85 a groove extending across the teeth.

5. The combination of a chaser-carrying frame having a reduced sleeve portion with external longitudinal teeth formed on it, a driving frame surrounding said teeth and 90 abutting the shoulder provided by the reduction in external diameter of the sleeve portion, a pawl carried by said driving frame and adapted at its inner edge to engage said teeth, said pawl having a projection adapted 95 to engage a groove formed across the teeth of the said sleeve.

6. The combination of a chaser carrying frame with longitudinal teeth, an oscillatory frame surrounding said teeth, a pawl 100 carried by the latter frame and adapted to engage and feed the teeth or be forced outwardly on backward movement, said pawl having a wing and there being notches across 105 the teeth in a position to form an interrupted annular groove occupied by the wing, said wing extending circumferentially to a greater distance than the space between adjacent teeth on the chaser-carrying frame. 110

7. The combination of a chaser carrying frame having longitudinal teeth, an oscillatory frame surrounding said teeth, a pawl carried by the latter frame, said pawl having an abrupt face adapted to engage and feed the teeth and an inclined portion at the rear of the face adapted to engage the outer corner of the adjacent tooth and thereby cam the pawl backwardly, said pawl having a wing formed on its inner face and projecting inwardly therefrom, and there being notches across the teeth in a position to be occupied by the wing, said wing extending inwardly beyond the point of the pawl tooth whereby it may engage the chaser frame 115 120 125 tooth which the pawl tooth is clearing.

8. The combination with driving means of a chaser-carrying frame with notches in it, chasers occupying said notches, said head having an annular groove in its edge and the 130

chasers having notches registering with said groove, and a clamping plate secured to the head covering the edge thereof and having on its inner side a rib occupying said groove 5 and notches.

9. A chaser frame having a head with a notch, a chaser occupying said notch, there being a groove formed on the edge of the head, a notch across the chaser in registration with said groove, a clamping member having a rib occupying the groove and the notch in the chaser, and means for holding the clamping member to the head. 10

10. A chaser frame having a head with notches, chasers occupying said notches, there being a groove formed on the edge of the head, notches across the chasers in registration with said groove, a clamping ring having a rib occupying the groove and the 15 notches in the chasers, and pins carried by the chaser frame and occupying holes in the inner edges of the chasers. 20

11. A chaser frame having a head with notches, chasers occupying said notches, a

clamping ring, and means for holding the 25 clamping ring to the head, and shoulders on the ring at its inner face and on the frame at the other side of said notches, said shoulders engaging shoulders on the respective edges of the chasers to hold them in 30 place at both edges.

12. The combination of a head having a sleeve, an oscillating driving device surrounding the sleeve and having a ratchet engagement therewith, said head having radial 35 notches, chasers occupying said notches, a ring secured to the end of the head, and means comprising a rib on said ring engaging the outer faces of the chasers, and projections extending from the frame and engaging openings in the inner faces of the chasers whereby the chasers are engaged and held at both their outer and inner edges by the ring and head. 40

In testimony whereof, I hereunto affix my 45 signature.

IRAW. NONNEMAN.
